Inventor.

John H. Mears.

United States Patent Office.

JOHN H. MEARS, OF OSHKOSH, WISCONSIN.

Letters Patent No. 74,400, dated February 11, 1868.

IMPROVED MOP-WRINGER.

The Schedule referred to in these Letters Patent and making part of the same.

TO ALL WHOM IT MAY CONCERN:

Be it known that I, JOHN H. MEARS, of the city of Oshkosh, State of Wisconsin, have invented a new and improved Device for Wringing Mops; and I do hereby declare that the following is a full, clear, and exact description of the construction and operation of the same, reference being had to the accompanying drawings, making a part of this specification.

My invention consists in the use of a horizontal frame, arching forward at the top, the latter affording bearings for a roller, and has a hinged connection at the top with vibratory arms, also supporting a roller. The rollers are brought in contact (over the platform wherein a pail may be set) through a connection from the vibratory arms to a lever, which is actuated by a treadle.

Figure 1 is a perspective view.

Figure 2 is a longitudinal section, the same being folded.

A A is a horizontal frame, supported on casters *i i i*. B B are upright standards, hinged centrally to frame A at *w*, and supported in position at option by hooks *s s*. C C are supplemental arms, forming a vibratory frame, which is hinged to the upper extremities of B B. E E are rollers, with journals, one each in B B and C C. D is an upright arm or spring-lever secured in D', and is actuated by treadle F—the spring *v* actuating a return motion. *g* is a bail or connection between the vibrating arms C C and lever D, connecting at *d''*. The mop is inserted, for wringing, between the rollers E E. The rollers are brought in contact by depressing the treadle F and actuating the arm D. The arm D also serves as a spring, and allows an elastic action between the rollers. The frame A A affords a platform whereon to set a pail beneath the rollers E E. By reason of the frame or standards B B being hinged to the horizontal frame A, and the bail *g* being detachable from the lever D, the wringer may be folded in a compact form, seen in fig. 2, convenient for placing away.

What I claim as my invention, and desire to secure by Letters Patent, is—

1. The hinging of the rectangular standards B B to the horizontal frame A A, the hooks *s s*, the hinged arms C C, and the detachable connection at *d''*, when arranged substantially as described for the purposes set forth.

2. I claim the hinged arms C C, the spring-lever D, and the bail *g*, when arranged relatively to each other and to the rollers E E, standards B B, frame A A, and treadle F, as and for the purposes set forth.

JOHN H. MEARS.
